CLAIM

The ornamental design for a leaf blower, as shown and described.

DESCRIPTION

FIG. 1 is a front, left, and top perspective view of a leaf blower, showing my new design;

FIG. 2 is a rear, right, and bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is an enlarged view of the encircled portion labeled "9" in FIG. 1.

The dot dash broken lines denote the boundaries of the encircled portion in FIGS. 1 and 9 and form no part of the claimed design. The evenly spaced broken lines in the drawings depict portions of the leaf blower that form no part of the claimed design.
